UNITED STATES PATENT OFFICE.

CHARLES S. LOCKWOOD, OF NEWARK, NEW JERSEY, ASSIGNOR TO HYATT ROLLER BEARING DIVISION, UNITED MOTORS CORPORATION, OF HARRISON, NEW JERSEY, A CORPORATION OF NEW YORK.

MORTISE-RIVETING.

1,275,576.

Specification of Letters Patent. Patented Aug. 13, 1918.

Application filed May 9, 1917. Serial No. 167,552.

To all whom it may concern:

Be it known that I, CHARLES S. LOCKWOOD, a citizen of the United States, residing at 496 Clinton avenue, Newark, county of Essex, and State of New Jersey, have invented certain new and useful Improvements in Mortise-Riveting, fully described and represented in the following specification and the accompanying drawings, forming a part of the same.

This invention relates to a particular means of securing the ends of tie-bars in flat heads, such as are employed in the cages for the rolls of roller-bearings and analogous constructions.

The invention consists in forming the end of the tie-bar with a tenon to extend through the head, by shouldering down the tie-bar for a sufficient distance, forming a groove in such a part of the tenon as would be inclosed in the mortise in the head, then applying the head to the tenon and forcing the metal of the head around the mortise inwardly, thereby pressing the head forcibly toward the shoulder while crowding the metal into the groove of the tenon, and thus locking the same permanently in the head with the shoulder tight against the head.

When it is desired to conceal the depression or counterbore formed by the tool around the outer end of the mortise, the tenon is projected through the mortise far enough to be expanded into the counterbore and thus finish the joint with a flush surface.

The invention is therefore applicable to any flat plate where the shouldered tenon can be projected through the plate and pressure applied to the plate opposite the shoulder to lock the tenon in the mortise, and simultaneously crowd the plate against the shoulder.

The nature of the invention and its mode of application will be understood by reference to the annexed drawing, in which Figure 1 is a section of a plate with a grooved tenon inserted therein; and Fig. 2 is a section of a tool adapted to press the metal around the tenon longitudinally of the tenon. Fig. 3 is a section of the same parts in Fig. 1, engaged by pressing the metal of the plate inwardly; Fig. 4 is a view analogous to Fig. 1 with the tenon projected outside of the plate; Fig. 5 is a

section similar to Fig. 3 with the metal of the plate compressed; and Fig. 6 is a section of the same parts with the projecting end of the tenon headed over.

Fig. 7 shows a tie-bar with grooved tenons at opposite ends.

A flat plate *a* is shown in the drawing to represent the head of a roller-bearing cage, and it has a mortise *b* extended entirely through the said plate.

The tenon *c* is shown formed upon the end of a rod *d*, by shouldering down the end of the rod, such a rod being shown in Fig. 7 as a tie-bar *d* having at its left-hand end a tenon with a rounded groove *e*, and at its right-hand end a beveled groove *e'*.

Fig. 2 shows an annular pressing tool or punch *b'* adapted to operate upon the metal surrounding the end of the tenon and to press such metal inwardly, as shown in Fig. 3 and force the metal of the plate *a* laterally toward the tenon, thus crowding it into the rounded groove *e*.

Such laterally moved metal forms an annular rib *g* which embraces the groove *e* like a tight collar, and wholly prevents the withdrawal of the tenon from the mortise.

In any construction where the counterbore *f* caused by the punch *f'* would be a disfigurement, the same may be concealed by forming the tenon originally to project outside the surface of the plate *A*, as shown in Fig. 4, the pressing tool being then operated to crowd the metal of the head into the groove *e* or *e'*, as shown in Fig. 5; and a subsequent pressure with a flat faced tool forces and expands the projecting end of the tenon into the counterbore *f*, as shown in Fig. 6, thus finishing the joint with a flush surface.

This construction of Fig. 6 forms an exceedingly rigid connection, as the metal of the plate or body *a* is forced into the groove of the tenon, and the end of the tenon is expanded into the recess *f*.

It will be observed that if the rod or tie-bar be firmly supported during the forcing of the metal into the groove *e*, the pressure of the tool *b'* upon the plate or head *a* will first force it into close contact with the shoulder and then lock the tenon in the mortise, thus automatically securing a tight joint between the tie-bar and the head, while securing the tie-bar therein.

This is a material advantage in connecting the heads with a number of tie-bars, as the shoulders upon the tie-bars are readily made at a uniform distance apart, and the 5 operation forces the heads as just described, closely against the shoulders and thus secures the heads permanently parallel with one another.

Having thus set forth the nature of the 10 invention what is claimed herein is:

1. The method of engaging a rod or bar with a cage-head having a mortise extended entirely through the same, which consists in shouldering down the said bar to form a 15 tenon with a shoulder at the base of the same, making an annular groove in the tenon, supporting the rod or bar against end-thrust with the cage-head resting upon the said shoulder during the engagement of 20 the rod or bar with the cage-head, the tenon and groove being proportioned to locate the entire groove within the mortise, and forcing inward the metal of the head around the outer end of the mortise, thereby holding

the head closely against the shoulder while 25 forcing the metal into the groove of the tenon.

2. The process of engaging a rod or bar with a plate having a mortise extended through the same, which consists in shoudering down the said bar to form a tenon with a shoulder at the base of the same, the tenon being proportioned to fit in and extend beyond the said mortise and having an 30 annular groove adapted to be located within the mortise, supporting the rod or bar against end thrust during the entire engagement of the same with the plate, then forcing inward the metal of the plate surrounding the outer end of the mortise, thereby 35 pressing the plate firmly against the shoulder and crowding the metal of the plate inwardly around the tenon and then heading over the outer end of the tenon into the depression thus formed. 40

In testimony whereof I have h^h unto set my hand.

CHARLES S. LC J. OD.
